(57) **CLAIM**

The ornamental design for a hose reel as shown and described.

DESCRIPTION

FIG. 1 is a front, right and top perspective view of a hose reel showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a rear, left and bottom perspective view thereof; and,

FIG. 9 is front, right and top perspective view thereof, showing parts of the hose reel in separated configuration. The evenly broken lines illustrate portions of the hose reel that form no part of the claimed design.

1 Claim, 9 Drawing Sheets

FIG. 1

FIG. 2

FIG. 3

FIG. 4

FIG. 5

FIG. 6

FIG. 7

FIG. 8

FIG. 9
